SUPPORTING STAND FOR GYMNASTIC PARALLEL BARS

George P. Nissen and Lawrence H. Conover, Cedar
Rapids, Iowa, assignors to Nissen Corporation, Cedar
Rapids, Iowa

Filed Nov. 1, 1961, Ser. No. 67,339

Term of patent 14 years

(Cl. D34—5)

FIGURE 1 is a perspective view of the supporting stand for gymnastic parallel bars embodying our new design; FIGURE 2 is a top plan view of the apparatus; and FIGURE 3 is a reduced end elevational view of the apparatus.

The broken line showing of parallel bars is for illustrative purposes only.

We claim:

The ornamental design for the supporting stand for gymnastic parallel bars, as shown and described.
